UNITED STATES PATENT OFFICE.

JOSIAH VAVASSEUR, OF SOUTHWARK, COUNTY OF SURREY, ENGLAND.

CENTER-PIVOTED MOUNTING FOR GUNS.

SPECIFICATION forming part of Letters Patent No. 373,623, dated November 22, 1887.

Application filed February 19, 1887. Serial No. 228,310. (No model.) Patented in France February 22, 1887, No. 181,740, and in Italy March 31, 1887, No. 21,265.

To all whom it may concern:

Be it known that I, JOSIAH VAVASSEUR, a subject of the Queen of Great Britain, residing at the London Ordnance Works, Bear 5 Lane, Southwark, in the county of Surrey, England, engineer, have invented certain new and useful Improved Center-Pivoted Mountings for a Rapid-Firing Gun, (for which I have obtained Letters Patent in France, No. 181,740, dated February 22, 1887, and in Italy, No. 21,265, dated March 31, 1887,) of which the following is a specification.

The base-plate, which is nearly flat, is provided with a central cylindrical pivot, around 15 which is a track for a series of balls of hardened steel. These balls support a center-piece of bronze, forming a part of a turn-table and adjustable by means of a screw-thread to insure that a due proportion of the weight shall 20 be supported upon the balls, while a comparatively light load is borne by wheels or rollers, which are provided at the periphery of the turn-table and which revolve upon radial axes. These wheels or rollers are conical on the face, 25 and they run upon a corresponding track on the base-plate. Clips are also provided upon the turn-table, and these embrace a flange upon the edge of the base-plate, so that there may be no risk of the turn-table being displaced 30 by the shock of the recoil. Upon the turn-table in front of the pivot there is fixed, in an upright position, a straight armor-plate, preferably of a height not to interfere with the sighting of the gun, and the upper edge of 35 this armor-plate is cut away in the center to form an embrasure for the gun. The armor-plate is supported in rear by another plate of the full depth of the armor-plate, and bent to a U form. The armor-plate forms a cross-tie 40 in front. This support also is firmly secured to the turn-table. It is cut away in rear nearly to the bottom to give passage to the breech end of the gun. On this U-form support an arm is fixed, terminating in a shoulder-piece, 45 by pressure against which the gun-mounting, with the gun upon it, can be turned to train the gun to bear upon the object. Upon the turn-table and on either side of the U-form support, where they are protected by the armor-plate, lockers are provided, in which about 50 a dozen rounds of ammunition can be stored.

On the upper part of the U-form support, near to the front, bearings are provided to receive trunnions formed upon a ring or hoop which is part of a frame in which the gun is 55 able to slide to and fro, recoiling always in the line of fire. The gun is preferably made without trunnions, and is suitably guided in the trunnioned frame, so that its direction is invariably maintained during recoil. This trunnioned frame is continued beneath the gun, and at its rear end it carries another ring, 60 which embraces the gun near its hinder end. The rings may also be connected together at the top. The gun-sights are fixed upon these 65 rings, and not upon the gun itself. In the part of this trunnioned frame extending from ring to ring beneath the gun a hydraulic control-cylinder is provided, and also a spring, which is compressed during the recoil of the gun and 70 afterward brings the gun forward again. The recoil-cylinder moderates the recoil and also the return movement, and for this latter purpose a plug is provided at the end of the cylinder, which enters a cavity in the face of the 75 piston or rod.

Beneath the gun, at the breech end, there is a lug, and to this lug the piston-rod of the piston working in the control-cylinder is attached. It passes through a gland in rear of 80 the cylinder. Two other rods are attached to the same lug. They project forward, passing one on either side of the control-cylinder to a cross-head, and against the back of this a base-disk at the end of the spring previously mentioned abuts. This spring, when the gun recoils, becomes compressed between the cross-head and the fore part of the control-cylinder, 85 which serves as the abutment for the spring. The spring does not bear directly upon the 90 control-cylinder, but upon the flange of a core-piece, which occupies the interior of the spring, and the base-disk at the other end of the spring is connected with the core-piece by a screw-stem, upon which it can slide. The stem serves 95 to apply to the spring a suitable initial compression. The arm on which is the shoulder-piece carries gear by which the gun can be elevated, and also locking-gear to restrain the training movement. The locking-gear consists of an inclined axis with a hand-wheel 100 upon it, and also a screw-thread near its lower

end. The screw-thread works in a corresponding screw-socket attached to the **U**-form support, and by turning the hand-wheel a shoe at the end of the axis is jammed against the face 5 of the base-plate, so the turn-table is rendered immovable. The elevating-gear consists of a horizontal axis with a hand-wheel at its outer end, and connected by beveled pinions with an axis on which is a screw-thread working into 10 a trunnion-nut supported by an arm projecting from the side of the hydraulic control-cylinder.

For the further protection of the gunners and mechanism, an outershield is also provided. 15 It also is of a **U**-form, with the convex part forward. In the upper edge of this convex part is cut the embrasure through which the gun projects, and this is of such dimensions as to admit of the gun being depressed as far 20 as may be considered necessary. The lower edge of this shield overlaps the edge of the base-plate and serves to protect it from injury. The ends of the straight armor-plate on the turn-table meet the shield on either side, and 25 are firmly fixed to it, and it is in this way that the shield is carried. The shield extends up on either side as far as may be deemed necessary for the protection of the gunners, and these side projections support a pivoted shutter-shield extending from side to side over the 30 gun. It can be turned down so that its edge meets the top of the armor-plate, and when in this position it is inclined at a considerable angle, and projectiles striking it are deflected, 35 so that this shutter-shield serves very completely to shelter the men from light projectiles. It is so mounted that if found to be in the way it can be readily removed or turned in a horizontal position, so as not to interfere 40 with the view in front of the gun.

In order that my said invention may be most fully understood and readily carried into effect, I will proceed to describe the drawings hereunto annexed.

45 In the drawings, Figure 1 is a plan of a gun-mounting constructed in accordance with my invention. Fig. 2 is an elevation, partly in section, of the same. Fig. 3 is a rear elevation. Fig. 4 is a vertical section of a portion 50 of the mechanism. Fig. 5 is a horizontal section taken on the line A-A in Fig. 4.

A is the base-plate. It is firmly secured to a suitable foundation. It has at its center a pivot, A', and around the pivot is a circular 55 groove, A², in which run balls supporting the upper parts of the mechanism. The base-plate has also an inclined roller-track around it at A³ A³, and it is provided with a flange, A⁴, to be embraced by clips on the turn-table.

60 B is the turn-table. It has an opening in the center, into which a bronze block, C, is screwed. This block bears upon the balls D, and at its under side is grooved to receive the balls. The block C is adjusted by screwing it more or 65 less far into the central hole of the turn-table B, so that while the main portion of the weight is taken on the block still the rollers at the pe-

riphery of the turn-table are not lifted from the roller-track A³. When the block C has been suitably set, it is fixed in position by locking-pins. 7c

E are rollers at the periphery of the turn-table. They are received into recesses prepared for them, and are carried upon radial pins or axes F F. As represented in the drawings, three rollers E—one in front and two in rear—are provided, and these will be found sufficient. 75

The turn-table is provided with a transverse vertical flange, B', to which an armor-plate, 80 or stout plate, which I shall term an "armor-plate," is attached. This plate is a main element in the mounting. The turn-table B is also provided with a curved flange, B², of horse-shoe form, to receive the **U**-form support in 85 rear of the armor-plate.

B³ B⁴ are clips which engage with the flange A⁴.

G is the armor-plate. Preferably it is sufficiently thick not to be penetrated or injured 90 by any of the lighter sort of projectiles. The mounting so made is much less liable to injury and the gunners are much better protected than if a lighter plate be employed. The plate G is arranged vertically and extends transversely across the turn-table, projecting on either side. At its bottom edge the plate G is firmly fixed to the flange B'.

H is a **U**-form support, of iron or steel plate, 100 in rear of the armor-plate G. It is riveted all around its lower edge to the flange B² on the turn-table. This **U**-form support stands up high on the two sides, where it has trunnion-bearings H' H' fixed to it, but in rear it is deeply cut away in order to allow of the gun 105 being elevated to a sufficient angle. This support H might be made in two separate pieces, one on either side; but it is preferable to make it in a single piece, and I shall speak of it throughout as if so made.

The trunnion-bearings H' H' receive into them the trunnions I' of the frame I. This trunnioned frame is composed in part of two rings, I² I³, the front ring, I², having the trunnions. These rings are connected beneath the 115 gun by a hollow cylindrical casing, I⁴, which is cast with the rings. The rings can also be connected on the top.

Within the part I⁴ the control mechanism is provided. 120

The gun is without trunnions, and is able to slide freely to and fro in the rings I² I³ of the trunnion-frame. It is prevented from turning by a longitudinal groove on the top of the casing I⁴, into which a key or keys fixed into the 125 gun are received.

L is the gun. It has at its rear end a lug, L', to which the rod M' of the piston M is fixed. The piston-rod passes through a gland, I⁵, into a cylindrical chamber, I⁶, containing oil or 130 other liquid. When the gun is forward, the liquid fills the entire capacity of the cylinder excepting that occupied by the piston and piston-rod. Narrow passages are provided in any

usual way, by which, when the gun recoils, the liquid in the cylinder is able to pass from the rear to the front of the piston, and preferably the passage is controlled so that as the recoil proceeds the area is diminished.

15 I' is a fixed plug in the cylinder I⁶, which, when the gun is forward, enters a corresponding cavity in the end of the piston-rod M'. It serves, when the gun moves forward, to bring it gradually to rest, the liquid in the cavity of the rod being able to escape past the plug with difficulty and comparatively slowly. The liquid is forced into the cavity during recoil through a transverse hole on the pressure side 15 of the piston.

L² L³ are rods connected with the lug L' upon the gun, and passing forward to a cross-head, L³. Against this cross-head the disk N, pressed forward by the coiled spring O, abuts.

20 P is a hollow core-piece occupying the interior of the coiled spring O. It is flanged outward at its rear end, and the spring bears upon the flange, holding it up to the end of the cylinder I⁶.

25 Q is a bolt passing through the disk N and screwing into the end of the core-piece P. This bolt Q thus confines the spring O, but allows it to be compressed as the gun recoils.

30 R is a curved shield fixed to the two ends of the armor-plate G. It extends down nearly to the ground-line, so as to protect the mechanism and gunners as efficiently as possible. It extends up on either side of the gun; but in front it is kept low, not to interfere with the 35 sighting of the gun or the view in front. The shield R carries a light pivoted shield, S, which at pleasure can be closed down until its lower edge rests upon the top of the armor-plate G. The gun-mounting is then completely closed in at the front, with the exception 40 of the openings, which are indispensable to the sighting and working of the gun.

45 T is an arm terminating in a shoulder-piece, T'. It is fixed to the support H on the left side. By lateral pressure against this shoulder-piece the training movement is imparted to the gun.

50 U is a hand-wheel on the axis U'. Its upper end is received into a bearing on the arm 55 T, and its lower screw-threaded end into a screw-socket, B*, upon the turn-table. By turning the hand-wheel U a shoe at the lower end of the locking-axis U' is caused to press against the roller-path A³ on the base-plate, and so the turn-table is locked to the base-plate, and the gun cannot be further trained until released.

V is the hand-wheel for elevating. It is on a horizontal axis carried upon the same arm, 60 T, with the shoulder-piece. By beveled pinions the elevating-axis gives motion to the screw W, and this works with a trunnion-nut,

W', which is mounted on the side of the under part, I⁴, of the trunnioned frame.

65 X X are ammunition-lockers, well sheltered from the enemy's fire by the armor-plate G.

Y is the fore sight carried by the ring I², and Z is the tangent-sight carried by the ring I³.

I claim—

1. In a gun-mounting, the combination, with the base having the roller-track around it, the central pivot, the annular groove around the pivot and the edge flange, of the turn-table, the block adjustably secured at the center of the turn-table, the balls in the groove around the pivot of the base and borne upon by said block, the rollers of the turn-table traveling upon the track of the base, and the clips secured to the turn-table and engaging the edge 80 flange of the base, substantially as and for the purpose set forth.

2. In a gun-mounting, the combination of the turn-table, the transverse armor-plate fixed thereto, the support fixed to the turn-table in rear of the armor-plate and having the trunnion-bearings, and the trunnioned frame mounted in said bearings, substantially as and for the purpose set forth.

3. The trunnion-frame and control apparatus, consisting of the rings I² I³, connected by the part I⁴, beneath the gun, the cylinder I⁶ within the part I⁴, the piston M, with its rod M', fixed to a lug on the breech of the gun, and the spring O, compressed on recoil by the 95 cross-head L³, which is also connected with the lug on the gun, substantially as described.

4. In a gun-mounting, the combination of the turn-table, the transverse armor-plate fixed thereto, and the curved shield fixed to the ends 100 of the armor-plate, substantially as and for the purpose set forth.

5. In a gun-mounting, the combination of the base, the turn-table, the support H, fixed to the turn-table, the arm fixed to the support 105 and having the shoulder-piece, the locking-axis having bearing at its upper end in said fixed arm and screw-threaded at its lower end, the screw-socket on the turn-table, through which the locking-axis works to press against 110 the base, the hand-wheel on the locking-axis, the elevating-axis having bearing in said fixed arm, its hand-wheel, the screw geared with the elevating-axis, the trunnion-nut with which the screw works, and the trunnioned frame 115 mounted in the trunnion-bearings of the support H and carrying the trunnion-nut, substantially as and for the purpose set forth.

JOSIAH VAVASSEUR.
